UNITED STATES PATENT OFFICE.

HARVEY J. YAGER, OF SEATTLE, WASHINGTON.

SIGNAL-CONTROLLING MEANS FOR RAILWAY-CROSSINGS.

1,247,477.

Specification of Letters Patent. Patented Nov. 20, 1917.

Original application filed October 8, 1915, Serial No. 54,840. Divided and this application filed December 9, 1916. Serial No. 135,963.

To all whom it may concern:

Be it known that I, HARVEY J. YAGER, a citizen of the United States, residing at Seattle, in the county of King and State of Washington, have invented certain new and useful Improvements in Signal-Controlling Means for Railway-Crossings; and I do hereby declare the following to be a full, clear, and exact description of the invention, such as will enable others skilled in the art to which it appertains to make and use the same.

The invention relates to signal controlling means for railway crossings and other intersecting rails and the present application is a division of an application filed by me October 8, 1915, Serial #54,840.

The object of the present invention is to provide simple, practical and efficient signal controlling means for railway crossings and other intersecting rails and to enable an oscillatory or vibratory member of a railway crossing to close a circuit and to operate a signal for indicating that the said oscillatory or vibratory member is in one position and for closing a circuit and operating another signal when the vibratory or oscillatory member is in another position, whereby the said signals will indicate the position of the movable parts of the railway crossing.

A further object of the invention is to provide signal controlling contacts or mechanism of this character designed for use in connection with rotary frog members and capable of indicating the position of the frog members which form a continuous tread for one track and bridge the grooves or spaces of the intersecting track.

With these and other objects in view, the invention consists in the construction and novel combination of parts hereinafter fully described, illustrated in the accompanying drawing, and pointed out in the claims here-to appended; it being understood that various changes in the form, proportion, size and minor details of construction, within the scope of the claims, may be resorted to without departing from the spirit or sacrificing any of the advantages of the invention.

50 In the drawings.

Figure 1 is a plan view of a railway crossing provided with signal controlling contacts constructed in accordance with this invention.

Fig. 2 is a vertical sectional view taken 55 longitudinally of one of the pairs of oscillatory arms.

Fig. 3 is a transverse sectional view on the line 3—3 of Fig. 2.

Fig. 4 is a vertical sectional view through 60 one of the corners of the crossing.

Fig. 5 is a detail sectional view of one of the oscillatory arms.

Fig. 6 is an enlarged detail view of one 65 set of the contacts.

Like numerals of reference designate corresponding parts in the several figures of the drawings.

In the accompanying drawings in which is illustrated the preferred embodiment of the invention as applied to a railway crossing, 1 designates rails arranged in pairs at right angles to each other and connected at their ends to corner bearing plates 2, connecting the rails 1 and also connected with outer rail sections 3. The crossing is provided at each of the rails with a flangeway or groove 26 and each of the corner plates is provided in its upper face with a cylindrical bearing recess or socket 34 receiving a circular rotary frog member 35 provided with a flangeway or groove 36 adapted to be arranged in alignment with the flangeways or grooves of the intersecting rails to form a continuation of the grooves or ways for safely guiding the 80 flanges of a wheel at the crossing. The frog member is provided at opposite sides of the groove 36 with tread faces 37 which are arranged in the same horizontal plane as the tread faces of the heads of the rails. As 90 explained in the said application the corner bearing plates and the rotary frog members are adapted to form a continuous tread surface and a continuous flangeway or groove at each intersection of the rails so that all 95 hammering of the wheels of a car or the like at the intersecting rails is eliminated.

Each of the rotary frog members is provided with a centrally arranged descending stem 39 on which is mounted a gear element 100 44. The gear element 44 of the rotary frogs are actuated by oscillatory arms or bars 48 and 49 disposed diagonally with relation to the crossing and provided at their outer ends with gear elements 50 and 51. The 105 gear elements 50 and 51 are substantially in the form of racks, the teeth of the gear element 50 of the oscillatory bars or arms 48

extending outwardly from enlarged terminal portions of the said arms or bars. The other set of arms 49 are provided intermediate of their ends with deflecting bends 52 which arrange the body portions of the said arms 49 below the plane of the other arms 48 and enable the said arms 49 to extend beneath the stems upon which the coacting gear elements are mounted. The arms or bars 49 are provided at their outer ends beyond the stems with flanges 53 having inwardly projecting spur teeth constituting the gear elements 51. The gear elements of the stems contiguous to the gear elements 51 are arranged reversely of the gear elements of the other stems in order to mesh with the inwardly projecting teeth of the gear elements 51 of the arms or bars 49. This arrangement effects a rotary movement of some of the frog members clockwise and other of the frog members counter-clockwise when the arms or bars 48 and 49 are oscillated in the same direction.

The inner ends of the oscillatory arms or bars are mounted on a vertical rotary support or pivot 59 having upper and lower journal or pivot portions 60 and 61 and set in a bearing 62 of a bottom plate 63. The upper journal or pivot portion 60 is mounted in an opening 73 of an upper bearing plate 74 which is bolted or otherwise secured to an approximately rectangular support 76 bolted or otherwise secured to the bottom bearing plate 63. The oscillatory arms or bars are actuated by the means of electro-magnets 99 and coacting electromagnets 100 arranged and operating as set forth in the aforesaid application and as the particular construction of the railway crossing and the means for actuating the same form the subject matter of the aforesaid application further description and illustration thereof are deemed unnecessary.

Mounted upon the inverted U-shaped support 86 are contacts 109 and 110 consisting of plates arranged in pairs and mounted in insulators 111. The insulators 111 are secured in suitable supports or brackets 112 of approximately Y-shape composed of spaced sides and a connecting portion from which depends a centrally arranged stem. The stem pierces the top of the support 86 and is threaded for the reception of a nut as clearly shown in Fig. 5 of the drawings. The contact plates or pieces 109 and 110 which are designed to be connected with signal light wires 109^a and 110^a are arranged in pairs at opposite sides of the support and the contact plates 110 which are of greater length than the contact plates 109 are resilient and are adapted to be sprung into engagement and electrical contact with the plate 109 whereby one of the signal light circuits will be closed when the oscillatory

bars or arms are in each position. The members of each pair of contacts are longitudinally disposed with relation to each other and are laterally offset from each other. The thickened portion 80 of the oscillatory arm or bar 48 carries an actuating or circuit closing piece 113 constructed of non-conducting material and secured to the said thickened portion 80 by a screw 114 or other suitable fastened device.

The contact actuating piece or member 113 is approximately U-shaped and it has depending sides located at the side edges of the thickened portion of the oscillatory bar or member 48 and the said sides are adapted to flex the contact 110 and force the same into engagement with the contacts 109. When the oscillatory arms or bars are moved in one direction by the energizing of the stationary electro-magnets 99 and the movable electro-magnets 100 the latch bolts are withdrawn by the energizing of the latch operating magnets 91 and as soon as the latter are deenergized by the cutting off of the current the spring operates to force the latch bars upwardly into their engaging position.

What is claimed is:—

1. A device of the class described including a pivotally mounted oscillatory arm, a frog member operatively connected with the said arm, pairs of contact plates located at opposite sides of the oscillatory member, the members of each pair of contact plates having inner engaging portions and extending in opposite directions, means connected with the other ends of the contact members for supporting the same normally out of contact, and a circuit closing member carried by the oscillatory arm and arranged to move the inner ends of the contact members into engagement with each other and operating between the supporting means of the said contact members.

2. A device of the class described including an oscillatory arm, a frog member operatively connected with and actuated by the arm, spaced brackets arranged in pairs at opposite sides of the oscillatory arm, the members of each pair being located at different distances from the pivot of the arm, contact plates arranged in pairs and secured to the brackets and extending inwardly into the spaces between the same and disposed longitudinally of the said arm and designed to be connected with the wires of a signal light circuit, and a circuit closing member mounted on the oscillatory arm and movable into and out of the spaces between the said brackets for carrying the contact members into engagement with each other.

3. A device of the class described including spaced brackets, an oscillatory arm movable between the brackets, said brackets

being arranged in pairs and having approximately U-shaped upper portions, a frog member operatively connected with the said arm, insulators mounted in the brackets, 5 contact plates supported by the insulators and a circuit closing member of non-conducting material carried by the oscillatory arm and arranged to move the contact plates into engagement with each other at the end

of each oscillatory movement of the said 10 arm.

In testimony whereof I affix my signature in presence of two witnesses.
